UNITED STATES PATENT OFFICE.

MAURICE J. WOHL AND HARRY HERTZBERG, OF NEW YORK, N. Y., ASSIGNEES TO ECONOMY ELECTRIC COMPANY, A CORPORATION OF NEW YORK.

DESIGN FOR A REFLECTOR FOR ARC-LAMPS.

No. 40,087.

Specification for Design.

Patented June 8, 1909.

Application filed March 26, 1909. Serial No. 486,064. Term of patent 14 years.

To all whom it may concern:

Be it known that we, MAURICE J. WOHL and HARRY HERTZBERG, citizens of the United States, and residents, respectively, of the city of New York, borough of Manhattan, county and State of New York, and of the city of New York, borough of Brooklyn, county of Kings, and State of New York, have invented a new, original, and ornamental Design for a Reflector for Arc-Lamps, of which the following is a specification, reference being had to the accompanying drawing, forming part thereof.

Figure 1 is a plan view and Fig. 2 a side elevation of a reflector showing our new design.

The design comprises a reflector of circular form having a contracted upper portion concaved in outline and an enlarged outwardly and downwardly flaring lower portion having a combined concave and convex outline.

We claim:

The new and ornamental design for a reflector for arc lamps as shown and described.

MAURICE J. WOHL.
HARRY HERTZBERG.
